CLAIM

The ornamental design for a personal fan with lanyard, as shown and described.

DESCRIPTION

FIG. 1 is a front, left side perspective view of a personal fan with lanyard showing our new design;

FIG. 2 is a rear, left side perspective view thereof;

FIG. 3 is a front elevational view thereof;

FIG. 4 is a rear elevational view thereof;

FIG. 5 is a left side elevational view of the personal fan with lanyard of FIG. 1 shown without the lanyard;

FIG. 6 is a right-side elevational view thereof;

FIG. 7 is a top plan view thereof;

FIG. 8 is a bottom plan view thereof; and,

FIG. 9 is a front elevational view of the personal fan with lanyard of FIG. 1 shown without the lanyard in an alternate position.

Broken lines illustrate portions of the personal fan with lanyards that form no part of the claimed design.

1 Claim, 9 Drawing Sheets
